MOTOR CONTROL.

1,069,060.

Specification of Letters Patent.

Patented July 29, 1913.

Application filed November 8, 1910. Serial No. 591,271.

To all whom it may concern:

Be it known that I, ERNEST L. GALE, Sr., a citizen of the United States, residing at Yonkers, in the county of Westchester and State of New York, have invented a new and useful Improvement in Motor Control, of which the following is a specification.

My invention relates to a system of control and has for one of its objects the prevention of arcing at the contacts of the reversing switch.

Another object is to prevent the operation of the reversing switches in rapid succession.

15 Other objects will appear hereinafter.

The accompanying drawing illustrates my invention as employed in a system of control for an electric elevator.

In this drawing is shown a motor M, its 20 brake B, a traction drum D, cable 6, a car C and counterweight W.

The controlling apparatus comprises a potential switch P, controller switch K, reversing switches R, R', accelerating magnet A, fast speed magnet F, final accelerating magnet E, stop magnet S, and auxiliary stop magnet X. Current is supplied through mains designated + and -.

To actuate the motor M a hand lever 11 25 of the controlling switch K is turned to the right or left of a central or stop position to energize either reversing switch R or R'. When a reversing switch is closed, the brake B is lifted and the motor is impelled 30 in a proper direction. To increase the speed of the motor the hand lever is turned farther in the same direction and the fast-speed magnet F, the accelerating magnet A and the final accelerating magnet E are energized and operated in the order named.

The auxiliary stop magnet X is in the common connection leading to the two reversing switch magnet windings and its contacts 12 are separated to break the connection for the stop magnet S whenever either reversing switch is energized. In stopping the motor, the stop magnet S is energized as soon as the hand lever 11 is returned to a central position, and a back contact 13 on 45 one of the stop magnet contacts prevents a circuit being closed through a reversing switch as long as the stop magnet is energized. These reversing switches are of the type joined by a rocking arm adapted to 50 press one switch down on the lower or back

contacts when the other switch is energized and making connection with the top contacts, and to allow only one switch to rest on the lower contacts when neither switch is energized.

There are three fields for the motor M; a series field in two sections, one having the terminals 41 and 42, and the other having the terminals 42 and 43; a shunt field with the terminals 43 and 44; and an extra field 65 with the terminals 44 and 45 which is energized only when the motor is being stopped.

A detailed description of the circuits and various operations will now be given. Let it be assumed that the potential switch is in 70 the "up" position or closed, a circuit being completed from the lead 14, through the potential switch holding coil 15, lower and upper limit safety switches 16 and 17 to the lead 18. As soon as the hand lever 11 75 in the car C is thrown over, say to the left, a circuit is completed from the negative main by way of conductor 19, contact 20, contact segment 21, contact 22, conductor 23, winding 24, conductor 25, auxiliary stop 80 magnet winding 26, conductor 27, contacts 28, 13, conductor 29, lead 14 to the positive main through the potential switch contacts. This circuit causes the reversing switch magnet R' and the auxiliary stop magnet 85 X to be energized and operated. As soon as the reversing switch is closed, an energizing circuit is closed for the brake B through the auxiliary contacts 47 of the reversing switch, and an armature circuit for the 90 motor which is traced from the positive lead 14 through the upper contacts 30 of the reversing switch, and by way of the switches R', R, and conductor 31 to the lower contact 32 of the latter switch, thence by contact 33, conductor 34 to and through the motor armature and by way of conductor 35, contacts 36, 37, conductor 38, through the entire starting resistance 39, conductor 40, to terminal 41, thence through the motor 100 series field to terminal 43, and by way of lead 18 to the negative main. The shunt field of the motor receives current as soon as a reversing switch is closed, by way of negative lead 18, to terminal 43, through the 105 shunt field to terminal 44, and thence by conductor 46 to and through the reversing switch contacts 30 to the positive lead 14.

To accelerate the motor M the hand lever 11 is turned farther in the same direc- 110

tion until the segment 21 makes connection with the contact 48, to close a circuit for the fast speed winding 49. When the fast speed magnet is operated the back contacts 50 are separated, the main contacts 51 and the auxiliary contacts 52 and 53 are joined. The main contacts 51 short circuit a portion of the starting resistance 39 to the point 1, and the auxiliary contacts lose a circuit from the point 10 of the starting resistance by way of conductor 54, contacts 52, 53, conductors 55, 56, contacts 57, 58, conductor 59, through the accelerating magnet winding, thence by way of conductors 46 and 31 to and through the reversing switch back contacts to one side of the motor armature. It is seen that the winding of the accelerating magnet A is connected in series with a portion (from the point 1 to point 10) of the starting resistance 39, across the motor armature and is subject to the voltage at the armature terminals. The accelerating magnet operates successively to short-circuit portions of the starting resistance, the last contact 60, the series field from terminals 41 to 42 and carries an auxiliary contact 61 which in its closed position makes connection with contact 62, and closes a circuit connection from conductor 52 by way of contacts 62, 61, conductors 63, 64, through the final accelerating magnet winding 65, thence by way of conductor 66 to conductor 46. This causes the final accelerating magnet E to be energized and operated, separating the contact 57 from contact 58 and joining it with contact 67, thus opening the circuit of the accelerating magnet A and establishing a holding circuit for the magnet E by way of conductor 56, contacts 57, 67, and conductor 64, from the conductor 55 through the magnet winding 65. Joining the final accelerating magnet contacts 68, short circuits the entire starting resistance 39 and the series field of the motor impressing the full voltage of the mains upon the motor armature. This circuit is traced from the positive main by way of main lead 14, through upper contacts of reversing switch R' and lower contact of reversing switch R, conductor 34 to and through the motor armature, by conductor 35, contacts 36, 37, conductors 38, 69, contacts 68, main lead 18 to the negative main.

To stop the motor the hand lever 11 is returned to central position, the fast speed magnet F, the accelerating magnet E, the auxiliary stop magnet X and the reversing switch R' being de-energized in the order named. The auxiliary stop magnet contacts 12 being joined cause a circuit to be closed through the winding of the stop magnet S across the motor armature, the motor now acting as a generator. A circuit is also closed through the extra field of the motor 65 and the extra field resistance 70 in series

therewith. The first of these circuits is traced from the motor armature by conductor 34, contacts 33, 32, conductors 31, 46, 71, contacts 12, conductor 72, magnet winding of magnet S, conductor 73, contact 50, conductors 69, 38, contacts 37, 36, conductor 35 to and through the motor armature. The other circuit is traced from the same beginning and from conductor 46 to contact 44 through the extra field winding to contact 45, thence by conductor 74 through resistance 70 to conductor 73, thence to the armature terminal. The stop magnet S now being energized by current from the motor raises its contacts in succession to short-circuit portions of the extra field resistance 70. The back contact 13 is attached to one of the stop magnet contacts and when they are raised, the contact 13 breaks connection with the fixed contact 28, thus opening the path common to the auxiliary stop and reversing switch windings. As long as the stop magnet S is sufficiently energized to hold the back contact 13 up, neither reversing switch can be energized. The effect of this is to prevent the motor being energized in the same or a reverse direction too soon after the current supply to the motor is cut off and until the dynamic braking effect has been reduced to zero or nearly to zero. A result is to prevent dangerous arcing at the contacts of the reversing switches at the time when the motor is reversed. Without this arrangement it might happen that if an attempt were made suddenly to reverse the direction of the motor, there would be a rush of current at higher potential than ordinarily employed at the contacts of one of the reversing switches. This causes arcing of the contacts, sometimes "flashing-over" which is very dangerous and destructive, and should be avoided as much as possible. The connection of the armature circuit must not be changed when the motor acts first as a motor and then as a generator to constitute a dynamic brake, in the same direction of rotation, and this invention absolutely prevents the reversal of the armature connections until the armature comes to rest or nearly to rest. The extra field winding assists in bringing the motor more quickly to a stop, the energization of the stop magnet decreasing with the speed of the motor, and when it becomes reduced to a certain limit the contacts fall back, the back contact 13 making connection with the contact 28, to place the circuits and devices in their unoperated condition.

In case the potential switch is opened the lower contacts 78, 79 are joined, the extra field resistance 70 is short-circuited by the conductors 76 and 77, through the said contacts, thus increasing the strength of the extra field, and the potential stop resistance 75 is inserted in the motor armature cir- 130

cuit; both of these conditions are to effect a more powerful stopping effect on the motor. It is evident that with this arrangement, arcing of the contacts is reduced to a minimum, the rapid reversal of the motor is prevented, and the speed of the motor must become reduced to a certain extent before the motor can be again actuated in the same or the opposite direction.

10 I desire not to be limited to the exact embodiment of my invention herein set forth, as it is evident that those skilled in the arts to which this appertains may make various changes without departing from its spirit or scope.

15 What I claim is:—

1. In an electric controlling system, the combination of electro-responsive reversing switches, a stop magnet, a variable resistance controlled thereby and means in connection with said stop magnet to prevent one reversing switch from operating after the other has been deenergized until the stop magnet is deenergized.

25 2. In an electric controlling system, the combination of electro-responsive reversing switches, a stop magnet, a variable resistance in a dynamic circuit and controlled by said stop magnet, and means in connection with the stop magnet to prevent both reversing switches from being energized after one reversing switch has been deenergized until the stop magnet is deenergized.

3. In an electric controlling system, the combination of electro-responsive reversing switches, a stop magnet, a relay magnet in circuit with the reversing switch and controlling the stop magnet circuit, and means in connection with the stop magnet to open 40 a circuit lead of the reversing switch windings when the stop magnet is energized.

4. In an electric controlling system, the combination of electro-responsive reversing switches, sectional resistance, a stop magnet operative to short-circuit said resistance, and a back contact on the stop magnet to open the circuit of the reversing switch windings upon the energization of the magnet.

50 5. In an electric controlling system, the combination of electro-responsive reversing switches, means to energize either one of the reversing switches, a stop magnet having a circuit separate from the reversing switches, contacts in the circuit of the reversing switch windings operable by the stop magnet, and means energized simultaneously with the energization of either reversing switch winding to open the circuit of the stop magnet.

6. The combination with a motor, of reversing switches, sectional resistance in a dynamic circuit of the motor, a stop magnet operable to variably control said resistance, means to energize the stop magnet before

the direction of rotation of the motor can be changed, and means in connection with the stop magnet to open a circuit lead of the reversing switch windings upon the energization of the said magnet.

7. The combination with a motor, of reversing switches, a stop magnet, a back contact on the stop magnet to control the reversing switch magnet winding circuits, and an auxiliary stop magnet to open the stop magnet circuit when a reversing switch magnet is energized.

8. The combination with a motor, of reversing switches having a common lead, a stop magnet, an auxiliary stop magnet in circuit with the reversing switch magnet windings, a back contact on the stop magnet to open and close the common connection to the reversing switch magnet windings, and contacts operated by the auxiliary stop magnet to open the stop magnet winding circuit when a reversing switch magnet is energized.

9. The combination with a motor, of reversing switches having contacts to close energizing circuits to the motor and dynamic circuits for the motor, sectional resistance in a dynamic circuit of the motor, a stop magnet for the motor energized when the motor is being stopped and operable to variably control said resistance in accordance with the motor speed, and means in connection with the stop magnet to exclude the energizing circuits when the stop magnet is energized.

10. The combination with a motor, of reversing switches having contacts to close energizing circuits to the motor and stopping circuits for the motor, a stop magnet connected across the motor armature when the energizing circuits are broken, sectional resistances in parallel with said stop magnet and controlled thereby, and means in conjunction with the stop magnet to maintain the energizing circuits in "open" condition until the energization of the stop magnet reaches a prescribed limit.

11. The combination with a motor, of reversing switches having contacts to close energizing circuits to the motor and stopping circuits for the motor, a stop magnet connected across the motor armature when the energizing circuits are broken, resistance in parallel with and controlled by the stop magnet, and means in conjunction with the stop magnet to maintain the energizing circuits in "open" condition until the motor reaches a predetermined speed.

12. The combination with a motor, of reversing switches having contacts to close energizing circuits to the motor and stopping circuits for the motor, a stop magnet connected across the motor armature when the energizing circuits are broken, sectional resistance in parallel with the stop magnet

and controlled thereby, and means in conjunction with the stop magnet to maintain the energizing circuits in "open" condition until the armature of the motor has nearly 5 come to rest.

13. In an elevator controlling system, the combination of a motor, reversing switches therefor, a car switch for the reversing switches, a stop magnet for the motor, an 10 auxiliary stop magnet with its winding connected in a lead common to both reversing switch windings, means in connection with the auxiliary stop magnet to open the energizing circuit of the stop magnet when a 15 reversing switch is energized and to close the same when the reversing switch is not energized, and a back contact in conjunction with a stop magnet contact to make connection for the auxiliary stop magnet and a

reversing switch only after the stop magnet 20 contact is released to render the car switch ineffective until the said back contact connection is made.

14. In an electric controlling system, the combination of electromagnetic reversing 25 switches, a stop magnet, an auxiliary magnet in circuit with the reversing switch magnets, and switches in the stop magnetic circuit and the auxiliary magnet circuit and controlled respectively by the auxiliary magnet and 30 the stop magnet.

In testimony whereof, I have signed my name to this specification in the presence of two subscribing witnesses.
